UNITED STATES PATENT OFFICE.

CYRUS B. MERRIAM, OF DETROIT, MICHIGAN, ASSIGNOR OF ONE-HALF TO JAMES A. MERRIAM, OF DETROIT, MICHIGAN.

FASTENER.

Application filed August 16, 1920. Serial No. 403,658.

To all whom it may concern:

Be it known that I, CYRUS B. MERRIAM, a citizen of the United States of America, residing at Detroit, in the county of Wayne 5 and State of Michigan, have invented certain new and useful Improvements in Fasteners, of which the following is a specification, reference being had therein to the accompanying drawings.

10 In my Patent No. 1,337,938, granted April 20, 1920, there is disclosed a fastener that may be advantageously used as automobile hardware for holding the overlapping edges of side curtains, panels, or other members 15 adapted to cooperate with an automobile top in providing an inclosure for the upper portion of the automobile body.

This invention relates to the same class of fasteners and includes certain improvements which simplify the construction of the fastener, reduces the expense of manufacture, and somewhat enhances the appearance of the fastener.

My improvements will be hereinafter 25 more fully considered and then claimed, and reference will now be had to the drawing, wherein—

Figure 1 is a front elevation of the fastener in an open position;

30 Fig. 2 is a longitudinal sectional view of the same;

Fig. 3 is a front elevation of the fastener in a closed position;

Fig. 4 is a longitudinal sectional view of 35 a portion of the same;

Fig. 5 is a cross sectional view of a detached rotatable member;

Fig. 6 is a perspective view of a detached steering member;

40 Fig. 7 is a front elevation of a fastener showing a slight modification of my invention, and

Fig. 8 is a cross sectional view of the same.

In the drawing, the reference numeral 1 45 denotes a long stud or bolt having a rounded outer end or head 2 provided with an annular groove 3. At the inner end of the stud or bolt is a peripheral flange 4 by which the bolt may be connected to a curtain 5, automobile body or the like.

It may be attached to the curtain 5 by a securing member 6 having prongs 7 extending through the curtain 5 and indent or clenched on the flange 4 to secure it against 55 the curtain 5.

8 denotes a piece of material, for instance, a curtain, having an opening 9 through which the stud 1 is adapted to extend. Surrounding the opening 9 is a grommet composed of a front plate 10 and a back 60 plate 11, said front plate having prongs 12 extending through the piece of material 8 and indent or clenched on the back plate 11. The front and back plates have openings 13 registering with the opening 9 so 65 that the stud 1 may extend through the grommet.

14 denotes another piece of material, similar to the piece of material 8, and this piece of material is sandwiched between a 70 back plate 15 and a holding member 16, said piece of material, the back plate 15 and the holding member 16 having registering openings, generally designated 17, so that the stud 1 may extend therethrough. The 75 holding member 16 has a series of prongs 18 extending through the piece of material 14 and indent or clenched on the back plate 17. The back plate 17 and holding member 16 cooperate in forming somewhat of a 80 grommet for the piece of material 14.

On the holding member 16 are opposed retaining members 19 which, as shown in Figs. 1 to 4 inclusive are in the form of rivets or pins having heads. The retaining 85 members 19 extend through opposed segment shaped slots 20 in a rotatable member 21 and said rotatable member has opposed finger pieces 22 preferably formed by pressing out portions of said rotatable member. The rotatable member has an eccentrically disposed opening 23 providing clearance for the head 2 of the stud 1 when the rotatable member 21 is in an open position, as shown in Fig. 1, and after the 90 pieces of material are placed together or in proximity to each other, as shown in Fig. 2, the member 21 may be partially rotated to shift the opening 23 out of alignment with the openings 17, thereby causing a 100 marginal edge or wall of the opening 23 to engage in the annular groove 3 of the stud 1, as best shown in Figs. 3 and 4. Rotation of the member 21 is limited by the retaining members 19 and the end 105 walls of the slots 20 define the open and closed positions of the rotatable member 21. It is the eccentric relation of the opening 23 relative to the peripheral edges of the rotatable member 21 that permits of said 110

rotatable member engaging in the stud groove 3 when partially rotated in one direction, and this locking principle is embodied in Figs. 7 and 8, but other retaining members 24 are employed for retaining the rotatable member 21 on the holding member 16. The retaining members 24 are in the form of lugs cut and stamped from the holding member 16 to extend through the slots 20 of the rotatable member and on to said rotatable member, it being understood that the lugs are bent after the rotatable member is placed on the holding member.

In either form of fastener the holding member may have opposed upstruck portions or teats 25 and the rotatable members, adjacent the finger pieces 22, may have upstruck or raised portions 26 to snap into engagement with the teats 25 and thus prevent accidental shifting of the rotatable members.

What I claim is:—

1. In a fastener, the combination of a stud, a holding member having a concentric opening to receive the stud, a rotatable member on said holding member having an opening eccentrically disposed relative to the concentric opening of said holding member and adapted to be shifted into registration with the holding member opening to

receive said stud and permit of said rotatable member engaging in said stud when partially rotated to place the rotatable member opening in eccentric relation to the holding member opening, and retaining members on said holding member extending through said rotatable member and retaining said rotatable member on said holding member to limit the rotation of said rotatable member.

2. A fastener comprising a holding member, a rotatable member, said members being adapted for juxtaposition with the edges of said members constantly in matched relation and the holding member having a concentric opening and the rotatable member an eccentric opening, the member openings adapted to register to receive a stud, and means to facilitate shifting said rotatable member to place the opening thereof in eccentric relation to the opening of the holding member whereby the shifted rotatable member may hold the stud in both members.

In testimony whereof I affix my signature in presence of two witnesses.

CYRUS B. MERRIAM.
